BEER DRAWING DEVICE

Stephen Wanderski and Frank Konwinski,
Chicago, Ill.

Application March 15, 1940, Serial No. 324,198

4 Claims. (Cl. 225—3)

This invention relates to a device for removing beer from a keg, barrel or other container, the general object of the invention being to provide a sealed tube which is placed in the barrel or container by the wholesaler or brewer, with means whereby when the usual tap is put in place the seal will be released and the beer will flow through the connecting means to the faucet or spigot in the usual manner.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and

in which:

Figure 1 is a sectional view with parts in elevation showing the device in place in a keg.

Figure 2 is a top plan view of Figure 1.

Figure 3 is a section on the line 3—3 of Figure 1.

Figure 4 is a longitudinal sectional view through the device and showing part of the keg in section.

Figure 5 is a section on the line 5—5 of Figure 4.

In these views the letter A indicates a keg, barrel or other container which is provided with the usual metal bung or plug B which is threaded in a hole formed in the barrel. The letter T indicates a tap of the usual or any ordinary construction and this tap includes the body part 1 having its upper end threaded to receive the cap 2 which has a threaded bushing 3 fastened thereto which bears against a packing ring 4 when the cap is threaded to the upper end of the body 1. The body is also formed with an intermediate tubular part 5 for receiving the usual chuck 6 which is to be connected by a hose to a supply of air under pressure for introducing air into the container, a rubber valve member 7 being carried by the inner end of the chuck. The lower end of the body 1 is threaded to be threaded into a tubular member or sleeve 8 for bearing against a gasket 9 to press the gasket against a flange on the bung or plug B when the cap 10 on the lower end of the body 1 is threaded to the sleeve 11 provided with the flange 12 for engaging the flange of the bung, as shown in Figure 4. A short tube 13 has its lower end threaded into the bushing

3 and its upper end is threaded to receive a coupling 14 which connects a hose nipple 15 to the tube, a gasket 16 being located in the coupling 14 and bearing against the flanged lower end of the hose nipple 15, the hose which is to be placed over this nipple leading to the faucet at the bar or other place. A tube or pipe 17 is threaded in the lower end of the short tube or pipe 13 and passes through the body 1 in spaced relation to the internal walls of the body and has its lower end placed slightly below the lower end of the member 8 which engage the packing ring 9, the lower end of the tube 17 being threaded as shown. A long tube 18 passes in spaced relation through the tube 17 with its upper end flanged to provide a valve which engages a seat formed in the upper end of the short tube 13 with this part engaging the gasket 16 when the coupling 14 is threaded tightly to the tube 13. This tube 18 passes well beyond the lower end of the tube 17 so that it will pass into the barrel when the tap T is connected to the bung B by the member 11. The lower end of the tube 18 is reduced and formed with holes 20.

Located within the barrel and placed therein by the brewer or wholesaler is a tube assembly which includes a tube 21 having the holes 22 in its lower end and the upper end of this tube 21 is threaded into the lower end of a larger tube 23 and the upper end of the tube 23 is threaded on the lower end of a smaller tube 24 which has a packing ring 25 tightly engaging its upper portion. A coiled spring 26 encircles the tube 24 and has its upper end bearing against the packing ring 25 and its lower end against the upper end of the tube 23. A valve 27 of resilient material is located in the tube 23 and is pressed upwardly by a spring 28 which bears against a ring-shaped seat 29 engaging the top of the tube 21. This valve 27 is normally pressed by the spring 28 against a valve seat formed by the lower end of the tube 24 so that the valve closes the passage formed by the tube assembly and when put in place with the lower end of the tube 21 resting against the lower part of the barrel. This places the spring 26 under pressure so that it will press the packing ring 25 tightly against the bottom of the plug B so as to close the opening therein and the spring 28 will also hold the valve 27 against the lower end of the tube 24 so as to close and seal the passage formed by the tube assembly. Of course, a usual covering means is provided for the plug B to eliminate any danger of leakage. Then

when the retailer or other person receives the barrel he removes or loosens the coupling 14 so that the tube 18 can move upwardly and then the tap T is threaded to the plug or bung B by 5 the member 11 but before the tap is put in place a short tube 30 is threaded to the lower end of the tube 17, this short tube 30 having a flange 31 at its lower end. Then as the tap is being put in place this tube 30 will engage the packing ring 25 and force the same away from the plug B and after this is done the coupling 14 is tightened on the tube 13 which forces the tube 18 downwardly and causes its lower end to push the valve 27 off its seat so that the interior of 10 the tube 18 will be in communication with the lower part of the tube assembly, thus permitting the beer to pass through the tube 21 and tube 23 by the valve 27 and into the tube 18 and then through the nipple 15 and the hose to the 15 faucet at the bar. Of course the air introduced through the chuck 6 will pass through the tap into the top of the barrel to place the beer under pressure.

Thus the retailer or barkeeper is only required to place the tap in position and this will place the interior of the tap in communication with the barrel so that the liquid can pass from the barrel and as soon as the tap is removed the barrel 27 and the packing ring 25 20 will return to closing position and seal the barrel again.

As shown in Figure 5 the flange 12 is made in sectors to pass through slots b formed in the flange of the bung or plug B. Thus it is only necessary to place the flange part 12 opposite the slots or notches b and press the tap downwardly and then turn the member 12 to cause the flange part 12 to engage the unnotched parts of the bung flange after which the cap 10 is 30 turned to tighten the parts to compress the gasket 9.

Also as shown in Figure 3 the member 11 has grooves therein for receiving ribs 8' on the member 8 to hold the parts from turning while the 45 cap is being rotated.

It is thought from the foregoing description that the advantages and novel features of the invention will be readily apparent.

It is to be understood that changes may be 50 made in the construction and in the combination and arrangement of the several parts provided that such changes fall within the scope of the appended claims.

Having described the invention, what is 55 claimed as new is:

1. A beer drawing device comprising a tubular member adapted to be placed in a container having an opening therein and a bung closing the opening, a packing ring at the upper end of the tubular member, spring means for holding the ring in closing position on the bung of a container when the lower end of the tubular member is engaging the bottom of the container, an upwardly closing spring-pressed valve in the 60 tubular member for sealing the interior of the tubular member, a tap member, means for connecting the same with the bung of the container 65

and means carried by the tap for forcing the valve off its seat and the packing ring away from the bung when the tap member is put in place.

2. A beer drawing device for a container having an opening therein and a bung closing the opening comprising a tubular member having a valve seat intermediate its ends, a spring-pressed valve normally engaging the seat, a packing ring slidably arranged on the upper end 10 of the tubular member, spring means for holding the ring in position closing an opening in the bung of the container, a tap member, means for connecting the tap member to the bung, a tubular member at the lower end of the tap member for forcing the packing ring away from the bung when the tap member is put in place, a tube passing through the tap member and having its lower end formed with holes, said lower end of the tube forcing the valve off its 15 seat when the tap member is put in place.

3. A beer drawing device for a container having an opening therein and a bung closing the opening comprising a tubular member having a valve seat intermediate its ends, a spring- 25 pressed valve normally engaging the seat, a packing ring slidably arranged on the upper end of the tubular member, spring means for holding the ring in position closing an opening in the bung of the container, a tap member, means 30 for connecting the tap member to the bung, a tubular member at the lower end of the tap member for forcing the packing ring away from the bung when the tap member is put in place, a tube passing through the the tap member and 35 having its lower end formed with holes, said lower end of the tube forcing the valve off its seat when the tap member is put in place, a short tube extending from the upper end of the tap member and the upper end of the first- 40 mentioned tube having a part engaging the upper end of the short tube, a hose nipple, a coupling for connecting the same to the short tube and a gasket ring between the lower end of the hose nipple and the short tube and the upper 45 end of the valve displacing tube.

4. A beer drawing device comprising a tubular member adapted to be placed in a container having an opening therein and a bung closing the opening, a packing ring at the upper end 50 of the tubular member, spring means for holding the ring in closing position on the bung of a container when the lower end of the tubular member is engaging the bottom of the container, an upwardly closing spring-pressed valve 55 in the tubular member for sealing the interior of the tubular member, a tap member, means for connecting the same with the bung of the container and means carried by the tap for forcing the valve off its seat and the packing ring away from the bung when the tap member is put in place, and means for introducing compressed air into the tap member to pass through the same and through the bung into the top of the container.
